BARREL CONSTRUCTION

Allen Quimby, Portland, Maine, assignor to
 Northern Maine Plywood Company, Portland,
 Maine, a corporation of Maine

Application August 1, 1931, Serial No. 554,421

1 Claim. (Cl. 147—1)

This invention relates to barrels, and more particularly to cylindrical barrels having side walls made of ply-wood, the latter being in the form of a plurality of plies or thicknesses of veneer fastened together.

Generally stated, the object of the invention is to provide a novel and improved construction and arrangement whereby a barrel of this character is provided with pre-formed heads or end walls, for both ends of the barrel, said heads or end walls being each in the form of a pre-formed hoop having one edge thereof secured to the marginal or circular edge portion of the flat, or substantially flat, end wall, whereby the securing of the said hoop to the side walls of the cylindrical barrel, inside thereof, serves to effectively position the said end wall within the barrel.

It is also an object to provide a novel and improved method of manufacture, for characterizing the barrel constituting the invention, comprising the rolling or bending of the ply-wood side wall material into cylindrical form, and attaching the overlapping edges together, prior to the insertion of the two pre-formed heads or end walls in the cylindrical body, and prior to the fastening of any hoops to said preliminary cylinder of ply-wood material, as well as prior to the clinching of any staples by which said heads are fastened to the side walls and held in place, so that the ultimate barrel is characterized by the method of manufacture thereof.

It is also an object to provide certain details and features of construction, and method steps, tending to increase the general efficiency and desirability of a barrel of this particular character, and to reduce the cost of production thereof.

To these and other useful ends, the invention consists in matters hereinafter set forth and claimed and shown in the accompanying drawings, in which—

Fig. 1 is a front elevation of a barrel involving the principles of the invention, showing the side portion at the left in section, and showing the top head or end wall in position above the top of the barrel, ready to be inserted downwardly therein, after the barrel is filled.

Fig. 2 is a top view of the said barrel.

Fig. 3 is a side elevation of the upper portion of the barrel, illustrating one method of fastening the top cover or upper head in place.

Fig. 4 is a fragmentary sectional view of a portion of the top of the barrel, showing another method of fastening the top cover in place.

Fig. 5 is a fragmentary or detail view, showing

one form of lap-joint for the inside hoops of the barrel.

Figs. 6 and 7 are similar views, showing a different form of lap-joint for the inside hoops of the barrel.

Fig. 8 is a similar view illustrating a butt-joint for the inside hoops of the barrel.

Fig. 9 is a side view of a head or end wall made with the form of hoop shown in Fig. 8 of the drawings.

Fig. 10 is a vertical section of one end portion of the barrel, illustrating the use of an inside hoop or liner serving as a shoulder against which the pre-formed head, at either end of the barrel, may be fastened in place, thereby to form a substantially sift-proof closure for each end of the barrel, when it is desired to ship things of an impalpable powder-like nature in a barrel of this kind.

As thus illustrated, the invention comprises 75 cylindrical barrel walls formed of inside and outside plies 1 and 2, together with a middle or intermediate ply 3, the grain of the wood in the middle ply extending circumferentially of the barrel, and the grain of the wood in the inside and 80 outside plies extending longitudinally of the barrel. These plies are put together under pressure, preferably, and are held together by a waterproof glue or adhesive, whereby the three-thickness ply-wood thus formed is waterproof 85 and will not come apart when damp or wet. Preferably, the sheet of ply-wood thus formed is rolled into cylindrical form, as shown, and staples

4 are then driven through the overlapping portions of the sheet, to form a vertical seam or overlap for one side of the barrel. Preferably, the vertical edge of the inner portion of the overlap is scarfed or thinned down, as shown at 5 in Fig. 2 of the drawings, so that the inner surface of the 90 barrel is cylindrical, but the outer edge 6 of the lap-joint thus formed is not scarfed and remains the thickness of the sheet of ply-wood. In this way, both vertical edges of the sheet of ply-wood have clean edges, as the grain of the wood extends vertically in both the inner and outer layers 95 of the ply-wood, and for this purpose the scarfing of the inner portion of the overlap is on the outer surface thereof, whereby no portion of the intermediate and outside plies or layers is exposed 100 inside of the barrel, the inner surface of the barrel being formed entirely by the inner surface of the inside ply or thickness of the sheet of ply-wood from which the side walls are made. As 105 stated, this provides a clean vertical edge, both

110

inside and outside of the barrel, for the overlap joint or seam at one side of the barrel.

The pre-formed heads or end walls are preferably each formed of a hoop 7, having a flat, 5 disklike section of the same kind of ply-wood 8, fastened to one edge thereof by staples 9, in the manner shown, whereby the edges of the ply-wood, which with this kind of ply-wood are clean and smooth throughout the circumference of the 10 disk, are flush with the outer side or periphery of the hoop. With the grain of the wood in the middle or intermediate ply of the wall 8 extending at right angles to the grain of the wood in the two outer plies, it necessarily follows that, 15 with a flat and continuous wall of this kind, the staples 9 all have their heads disposed more or less crosswise of the grain of some of the wood of which the wall 8 is composed. Thus, with ply-wood of this kind, the anchorage thereof to the 20 hoop, which latter is preferably a pre-formed hoop, is very effective. The said hoop may have an ordinary lap-joint, as shown in Fig. 5, or its ends may be scarfed to form a scarf-joint, as shown in Figs. 6 and 7 of the drawings. Again, 25 a butt-joint of the kind shown in Fig. 8 of the drawings may be employed for these inside hoops of the barrel, depending upon the character of the produce or commodity to be shipped in barrels of this kind. The joint shown in Figs. 6 and 7, 30 for example, is adapted to provide practically a sift-proof bottom or top for the barrel, at least much more so than the joints shown in Figs. 5 and 8 of the drawings.

After the preliminary cylinder of ply-wood is 35 made, forming the side walls of the barrel, one of the pre-formed heads or end walls is then placed in position therein, and the ends of hoop strips for the outside hoops 10, 11 and 12 are placed in position on the outer surface of the 40 cylinder, and the latter is then rotated while staples 13, 14 and 15 are driven to secure the three outside hoops and the one inside hoop 7 in place, in the manner shown. The staples 13 and 14 are clinched on the inner surface of the cylindrical walls of the barrel, and the staples 15 are, 45 in the upper row thereof, similarly clinched, but the lower row of staples 15 have their ends clinched on the inner surface of the hoop 7 of the pre-formed head or end wall. Each outside 50 hoop has its inner end 16 butted against the outer edge 6 of the ply-wood side wall material, these outside hoops being preferably of the same thickness as the ply-wood material; and the outer end portion 17 of each outer hoop is stapled in place, 55 by the staples previously mentioned, and also by a wider staple 18 straddling the reduced end portion of the hoop. Thus, the inner ends of the outside hoops are first anchored in place, against the outer edge 6 of the veneer side wall material, 60 by staples, and these hoops are then wound around the barrel and gradually stapled in place in the manner shown, which operation also includes the fastening of the bottom head or end wall in place. With this method, the stapling 65 operations can be easily performed on suitable machinery having a rotary support for the barrel, and having staplers for inserting the staples.

When a scarf-joint is employed for the inside 70 hoops, as shown in Figs. 6 and 7, the staples 19 are inserted through such joint to hold the overlapping portions firmly together. Similar staples can be inserted through the lap-joint shown in Fig. 5, but in Fig. 8 there is no lap-joint and no such staples are necessary.

After the barrel is filled, the upper head or end

wall is then placed in position, as shown in Figs. 3 and 4 of the drawings, and its head or end wall can then be fastened in place in any suitable or desired manner, by nails, or staples, or other means. As shown in Fig. 3, staples 20 are inserted inwardly through the hoop 10 and the side walls of the barrel, and through the hoop 7 of the said pre-formed head or end wall. When the inner ends or points of these staples are clinched, as shown in Fig. 4, staples 21 are inserted outwardly through the hoop 7 and the side walls of the barrel and the outer hoop 10, and the points of these staples are clinched on the outer surface of the said outside hoop.

In some cases, in order to provide a more effectively sift-proof barrel, for impalpable or finely powdered materials, two additional inside hoops, such as the hoop 22, shown in Fig. 10, may be employed as liners or shoulders for properly positioning the two pre-formed heads or end walls, and for providing a tighter joint between the heads and the cylindrical barrel side wall material. These inside hoops or liners 22 may be secured in place in any suitable or desired manner, as by staples 23 inserted inwardly 100 through the outside hoops and the side walls of the barrel at the same time that the outside hoops are stapled in place. The hoops 22, when employed, are preferably pre-formed hoops and are preferably placed inside of the preliminary cylinder formed by the ply-wood side material, and in such case the staples 23 may simply be the staples 13, or the staples in the upper row of the staples 15.

Thus, by one stapling operation, the preliminary cylinder of ply-wood is made; by other stapling operations, the pre-formed heads or end walls are made, by other machinery, either before or after the making of the said preliminary cylinder; thereafter, one of the pre-formed heads or 115 end walls is placed inside of the preliminary cylinder, flexible hoop strips are secured at one end of each strip to one side of the cylinder, with the ends of these strips butted against the outer edge of the ply-wood side material; and by another stapling operation, preferably by rotating the barrel, all of the hoops (except one), with which the ultimate barrel is provided, are stapled in place; and finally, after the barrel is filled, the last hoop, the one forming part of the top 125 cover or head, is stapled or otherwise fastened in place in the manner shown.

The resulting cylindrical barrel is light and surprisingly strong, and will stand much wear and tear and hard usage, without danger of 130 breakage, and without danger of leakage of the contents of the barrel, and the construction and method of manufacture employed tends to reduce the cost of production.

Thus, it will be seen that an inside shoulder 135 can be provided by the hoop 22, as shown in Fig. 10 of the drawings, for direct engagement with the end wall of the pre-formed head, but the flat side of the pre-formed head faces inwardly, and the end wall material is in direct engagement with 140 said shoulder.

It will be seen, from the foregoing, and from the drawings, that the method or process shown and described relates to the specific barrel construction shown and described, and is a method 145 of putting together the parts shown and described, in order to produce the particular barrel structure shown and described.

It will be seen that the invention, as shown and described, and as defined by the claim, re- 150

lates primarily and essentially to tight or entirely closed barrels, preferably of the cylindrical type. In the manufacture of such tight barrels, in accordance with the invention, the body is 5 essentially a one-piece three-ply veneer body with the grain of the wood extending crosswise in the different plies, and with a permanently stapled side seam or joint, whereby the three-ply body is capable in itself of maintaining its shape 10 and form, even without any hoops, so that the major part of the load strain, or the bursting strain, may be sustained by the body, instead of by the hoops, in a structure in which the barrel has preformed tight heads involving inside hoops 15 upon which the radial staples are clinched at the inner periphery of each inside hoop. This makes a very strong and tight barrel, preferably of the cylindrical type. A self-sustaining body of primary strength can be made as a unit, and 20 the preformed inside hoop heads can also be made, and the heads can then be combined with the preliminary cylinder. Outside hoops are added, as shown and described, but with the three-ply body of primary strength hoops are not 25 as essential, although desirable, as they are in ordinary barrels or containers in which the body has very little if any primary strength. Therefore, a solid three-ply permanently stitched self-maintaining body of primary strength, with at least 30 one preformed hoop head, all forming a perfectly tight barrel, is essential to the invention, the other features disclosed being built around that to accomplish the desired purpose.

Thus the side seam or lap-joint of the barrel 35 is permanently stitched, and by this is meant that the lap-joint is fastened together with staples or other means so strongly that it is not liable to give way or separate under the bursting strain, practically even without any outer hoops. Obviously, with the three ply veneer of sufficient thickness, without materially increasing the weight of the barrel, and with the joint or seam properly fastened, and formed as shown and described, the said seam or joint may become the strongest 40 portion of the side walls of the barrel, and in that sense it is permanently stitched and the cylindrical body is capable in itself of maintaining its shape and form against the bursting strain, and the outer hoops are more for the barrel to 45 roll on than they are to resist the bursting strain, and it will be seen that these are important considerations in connection with the incorporation of the preformed barrel heads, as the fasteners, such as staples, are driven through the outside 50 hoop and into and through the inside hoop, which latter forms a part of the preformed barrel head, and clinched on the inner surface of said inside hoop, thus for the first time forcibly compressing the three-ply veneer between inner and outer 55 hoops. Thus the three-ply cylindrical side walls are clamped tightly between the inner and outer hoops, at both ends of the barrel, and a very tight joint, approximating what might be called a liquid tight joint, is obtained by the radial staples 60 that have their points clinched on the inner side of the inside hoops. The staples 9 are tightly driven, to provide the preformed barrel head, so that a tight joint is also formed between the plywood disk 8 and the inside hoop 7, at each end 65 of the barrel, and in this way a very tight container is provided that is practically sift-proof, whereby various commodities, such as cement and other powder-like commodities, may be satisfactorily shipped in barrels of this kind. And, for this purpose, therefore, as previously explained,

the staples 9 are desirably driven before the staples 15 are inserted, in order to insure a tight joint between the disk 6 and the hoop 7, and in order to avoid any operation that would disturb the set of the staples 15 after the latter are inserted and clinched. 80

It will be seen that the outer surface of the plywood sheet used to form the drum in effect stretches when the plywood is bent into cylindrical form, and that the inner surface correspondingly shrinks or contracts, because the grain of the wood of the inner and outer surfaces extends longitudinally of the barrel. This makes it easy to bend the plywood into cylindrical form, and the middle ply then furnishes the strength necessary to resist the bursting strain, effectively, as shown and described. Furthermore, it is obvious that the finished barrel or container is characterized structurally by the initial fastening of the inner hoop 7 to the cylindrical body, which latter in effect forms a restraining hoop circumscribing the inner hoop, while the inner hoop and the disk 8 are solidly united. In other words, the staples 15 are inserted after the staples 9 are inserted, and hence the staples 9 are in place while 100 the staples 15 are being driven. In this way the set of the staples 15 is not disturbed by the insertion of the staples 9, and the inner surface of the side walls is not marred or injured by any effort to insert the staples 9 after the staples 15 are inserted. This means that the hoop 7 and the disk 8 are incorporated as a unit in the barrel structure, and that the finished barrel is characterized by this method of construction, as is discernible to one skilled in the art. The finished 110 container shows these characteristics, and shows that the bottom or barrel head is stronger and effective as the result of this method of construction. The reverse method, as explained, would plainly show a structural inferiority. 115

Whether the staples 15 are employed, or the staples 21, it is true that these staples have their points clinched on the exterior of the barrel, for the inner periphery of the hoop 7 forms a part of the exterior of the barrel, and the outer periphery of the hoop 10 is certainly a portion of the exterior of the barrel. Also, in either form of the invention, these radial staples pass through both the body and the preformed bottom unit, but in each case both the heads and the clinched 125 points of the staples are exposed on the exterior of the barrel, after the preformed bottom unit or head is fastened in place.

What I claim as my invention is:

In a barrel construction having opposite countersunk heads, the combination with a circumscribing annular body formed of a single sheet of flexible and multi-ply cross grain material overlapped and secured together at the ends thereof to provide a continuous side wall, of a countersunk barrel head comprising a preformed unit fitting snugly within one end of said body and secured thereto by staples passing substantially radially through the body and said unit and clinched on the exterior surface of the barrel, 130 said unit comprising a disc-shaped member of multi-ply cross grain material having approximately the same diameter as the interior of the body and an inside annular hoop having the same external diameter as the disc-shaped member, said hoop being secured to the exterior of said member by staples driven axially through said disc into said hoop to form said unit, so that the heads of said axial staples are close to the side wall, and an outer hoop of substantially the same 135 140 145

thickness as the sheet secured in place by said radial externally clinched staples and surrounding said body and having one end thereof abutting the outer edge of said sheet, the inner edge of the side wall overlap being thinned away to practically fit the periphery of said disc and its

hoop, and means forming a countersunk head for the other end of the barrel, whereby the latter may be rolled around and stood on either end with said preformed hooped unit serving as either the raised bottom or the countersunk top thereof. 80
